INTERNAL METAL LAP.

1,215,059.

Specification of Letters Patent.

Patented Feb. 6, 1917.

Application filed February 28, 1916. Serial No. 81,007.

To all whom it may concern:

Be it known that we, LORENCE S. RASMUSSEN and HERMAN B. CARLSON, a citizen of the United States and a subject of the 5 King of Sweden, respectively, residing at Rock Island, in the county of Rock Island and State of Illinois, and Davenport, in the county of Scott and State of Iowa, respectively, have invented certain new and useful 10 Improvements in Internal Metal Laps; and we do hereby declare the following to be a full, clear, and exact description of the invention, such as will enable others skilled in the art to which it appertains to make 15 and use the same.

This invention relates to grinding and polishing, and more especially to the internal treatment of curved surfaces; and the object of the same is to produce an improved 20 lap or tool which is intended to be rapidly rotated within a tubular piece of work so as to apply the abrading material thereto. A further object is to so construct the lap that it will adapt itself to work of slightly varying 25 sizes and to inequalities on the surface being treated.

These objects are carried out by the construction hereinafter more fully described and claimed, and shown in the drawings 30 wherein—

Figure 1 is a plan view of this improved lap, Fig. 2 is a longitudinal section on the line A—A of Fig. 1, Figs. 3 and 4 are transverse sections on the lines B—B and C—C 35 respectively of Figs. 1 and 2, and Fig. 5 is a longitudinal sectional view showing modifications or amplifications.

In common practice internal laps are mounted at one end in a lathe or drill press 40 and rapidly rotated, and the tubular piece of work to be treated is slipped over the lap and moved along the same so that all parts of its interior are treated. Often the work is slightly irregular or rough, and it becomes 45 desirable to have the lap yield slightly to accommodate itself to these irregularities. Also a tubular piece of work is sometimes initially produced in a size slightly larger or slightly smaller than 50 standard, and it is the purpose of our invention to cause this lap to adapt itself to these variations. We might say that in Figs. 1 and 2 such means for adaptation are shown in only one end of the tool, whereas in Fig. 5 55 they are shown at both ends thereof, and it

is our intention to cover both constructions or either.

Referring now to the drawings by reference numerals, 1 is the tubular body of this improved tool, its ends 2 and 3 being unbroken and that portion between said ends being provided with longitudinal slots 8 whereof three are shown in Figs. 3 and 4. This body is by preference made of metal and its outer face is truly cylindrical and 60 formed with a working surface 7 which grinds and polishes the interior of the tubular piece of work to be treated. The bore 4 is cylindrical and of considerable size near both ends of the body as best seen in Fig. 2, 65 but toward the center of the length of said body said bore is tapered or reduced so as to form conical seats 5, and the apexes of these seats are connected by a reduced or very fine bore 6 around which the wall of 70 the tubular body is somewhat thicker than elsewhere as shown. It follows that the ends of this tubular body at 2 and 3 cannot expand or contract, but on account of the slots 8 its intermediate portion may do so. 75 A strictly cylindrical piece of tubular work slipped over either end and along the body would contact with the working surface 7 throughout the length of the tool, but if the work were a trifle larger than either unbroken end the working surface would have 80 to be expanded or enlarged slightly in order to bring it into contact with the surface to be treated.

The expander or spreader is shown in Fig. 2 as a plug 10 having a conical point 11 which fits into one of the seats 5, the rear or outer end of the plug here having a pin 12. The unbroken end 2 is shown as having a threaded bore or opening 14 into which 95 passes a screw 16 having a pin 15 at its inner end. A coiled spring 17 is located within the bore 4 between said screw and plug, and its extremities engaged by the pins 12 and 15. The normal expansive force 100 of this spring tends to urge the spreader forward or inward against the seat 5 and distend the center of the body so as to enlarge the working surface 7, and it is obvious that adjustment of the screw would 105 increase or decrease the tension of the spring.

While we have shown the element 16 as a screw in Fig. 2, any adjustable plug would answer the same purpose, and its adjust- 110

ment would effect the increase or decrease of the tension on the spring. At the right end of Fig. 5 a plug is shown which will be described below. At the left end of this view the screw 16 is shown with a socket 15' instead of a pin, and the spring 17 is cupped as at 18 so as to embrace the spreader. The latter in this case is a ball 13 whose rear side is seated within the cup and whose front 10 or inner side is seated within the conical seat 5, but it is obvious that the action is the same as above described.

This view (Fig. 5) has also been made use of to illustrate the fact that spreaders 15 could be employed in both ends of the bore 4 and work on both the seats 5, and it will be understood without further illustration and description that the two spreaders could be alike or could differ as shown.

20 The plug within the other unbroken end 3 of the body is by preference smooth as shown at 20, although in fact it might be possible here also to use a screw. This plug is useful more especially for preventing crushing of this end of the tubular body when the same is clamped within a lathe or between jaws as shown at J J'; and, as one spreader will distend the center of the body and increase the size of the working surface 7, it 30 is not in all cases necessary and indeed it is sometimes not desirable that this plug shall also be used in connection with a spreader. However, in Fig. 5 we have shown such a spreader at 21 having a pin 22, and the plug 35 20 as having a pin 25, and between these two elements a coiled spring 27 is disposed, so that it normally bears the spreader forward and forces its conical point into the seat 5. When the plug 20 is pressed inward to increase the tension on this spring, it must be 40 held in that position by clamping the tool within some member as indicated at J J', and when this member is rotated the entire tool is rotated in the manner first above described. If a screw be used in place of the 45 plug 20, the head of the screw should be smaller than the circumference of this end of the tool in order that the entire screw may be passed into the machine or between 50 the jaws which will be clamped upon it, and the clamping action while preventing the outward slipping of the plug will obviously prevent the unscrewing of the screw. It will also be obvious without further illustration 55 that the spreader may have a point which is of the same taper as the conical seat or of a different taper, or it may have a rounded point or a hemispherical point or faced like the inner side of the ball 13. The 60 idea is that when this spreader is pushed inward against the seat, the slotted and therefore yielding center of the body is spread or expanded—yet this expansive force is itself a yielding one by reason of the 65 presence of the spring, and if the work

should cause the compression or reduction in size of the working surface of the tool the seat would react on the spreader and push the latter backward against the force of the spring so that nothing would be broken. 79

In use, as is well known, the tool is inserted in some rotary member here indicated at J J' and rapidly rotated. The tubular work is then brought into position in the hands of the operator and passed over the 75 free end of the tool, and pushed up and down upon the same so that the working surface or expanded center of the tool is moved into contact with all portions of the interior of the tubular piece of work being treated. All 80 irregularities therein are ground off and a high polish is given to the product. In case the opening in the work has been drilled rather roughly but supposedly to standard size, it may be that it will be slightly larger 85 than that size and therefore—although it will pass over the unbroken end 2—when it reaches the center or working surface 7 of the tool the latter will not have that active contact with it which is necessary for grinding and polishing. The work is then withdrawn and the screw 16 set up a little so that the spring 17 is put under greater tension and the plug 10 forced forward. This expands the center of the tool, and when the 90 work is replaced thereon the working surface 7 is a little larger. The abrading material being applied, either to the exterior of the tool or the interior of the work, when now the tool is rotated rapidly as described, 95 the bore of the work is treated in the manner desired. If the work to be treated is a ring whose bore is of less length than the length of the tool shown, the action is the same excepting that the ring passes completely over 100 the tool and the outer end of the latter is exposed; and in this case the workman can observe what is occurring more easily than if the work were, for instance, a gun barrel. 105

What we claim is:

1. A tubular lap unbroken at its ends, its exterior being normally cylindrical throughout its length, and yielding means tending to spread the portion between said ends so as to enlarge the surface thereof. 110

2. An internal lap having between its ends an active surface which is normally substantially cylindrical, and yielding means tending to distort the shape of said lap between its ends and enlarge the circumference of 120 said surface without enlarging it at said ends.

3. A lap internally cylindrical and externally cylindrical and normally of one size throughout its length, and yielding means 125 movable longitudinally within the lap and tending to enlarge the size of the same between its ends.

4. A tubular lap unbroken at its ends and longitudinally slotted between them, its ex- 130

terior being normally of one size throughout its length, and yielding means tending to spread the slotted portion between said ends so as to enlarge the surface thereof.

5. An internal lap longitudinally slotted between its ends and hollow throughout its slotted portion, said portion having a normally cylindrical working surface, a spreader within said hollow portion for enlarging the body of the lap where it is slotted, and yielding means for advancing said spreader but permitting its recession.

6. An internal lap longitudinally slotted between its ends and hollow throughout its slotted portion, said portion having a normally cylindrical working surface, a spreader within said hollow portion for enlarging the body of the lap where it is slotted, a spring for advancing said spreader but permitting its recession, and means for adjusting the tension of said spring.

7. An internal lap slotted along its working face and tubular opposite the slotted portion, its bore having a tapering seat opposite said face, a spreader within said bore having its inner end engaging said seat, and yielding means bearing against its outer end and tending to advance the spreader and enlarge said working face while permitting the recession of the spreader as described.

8. A lap slotted along its working face and tubular opposite the slotted portion, its bore having a tapering seat opposite said face, a spreader within said bore having its inner end engaging said seat, a plug adjustably mounted in the adjacent end of the lap, and an expansive spring between said plug and spreader.

9. A tubular lap slotted along its working face, its bore having a tapering seat opposite said face, a spreader within said bore having its inner end engaging said seat, a screw threaded into the adjacent end of the lap, and an expansive spring between the screw and spreader.

10. A lap slotted along its working face and tubular opposite the slotted portion, its bore being reduced in size opposite said working face to form a conical seat, a spreader consisting of a plug slidably mounted in said bore and having a tapering point engaging said seat, a longitudinally adjustable member in the adjacent end of the lap, an expansive spring between the member and spreader, and means on such member and spreader engaging the ends of the spring.

11. In an internal lap, the combination with a tubular body whose ends are un-

broken and whose intermediate portion is longitudinally slotted, its bore at its mid-length being tapered to form two conical seats; of a spreader resting against one seat, a screw in the adjacent end of the bore, an expansive spring in such bore between the screw and spreader, and a smooth plug in the other end of the bore.

12. In an internal lap, the combination with a tubular body whose ends are unbroken and whose intermediate portion is longitudinally slotted, its bore at its mid-length being tapered to form two conical seats; of a spreader resting against one seat, a screw in the adjacent end of the bore, an expansive spring in such bore between the screw and spreader, a spreader resting against the other seat, an adjustable member in this end of the bore, and an expansive spring between this member and the adjacent spreader.

13. In an internal lap, the combination with a tubular body whose ends are unbroken and whose intermediate portion is longitudinally slotted, its bore at its mid-length being tapered to form two conical seats; of a spreader resting against one seat, a screw in the adjacent end of the bore, an expansive spring in such bore between the screw and spreader, a spreader resting against the other seat, a smooth plug longitudinally adjustable in this end of the bore, and an expansive spring between the inner end of said plug and the adjacent spreader.

14. In an internal lap, the combination with a tubular body unbroken at both ends and longitudinally slotted between them, its bore being tapered in opposite directions at its mid-length to form two conical seats, smooth from one seat outward through one end, and smooth from the other seat outward toward the other end and threaded through the unbroken portion of the latter; of a screw in said threaded portion of the bore, a longitudinally movable plug in the opposite end of the bore, expansive coiled springs in the bore next inside the screw and plug, and spreaders at the inner ends of the springs, each comprising a body movably mounted in the bore and a tapered point resting on said conical seats, the contiguous extremities of said points being separated by the reduced portion of the bore, as and for the purpose set forth.

In testimony whereof we affix our signatures.
